UNITED STATES PATENT OFFICE.

CARL E. PEARSON, OF CLEVELAND, OHIO, ASSIGNOR TO THE TEAGLE COMPANY, OF CLEVELAND, OHIO, A CORPORATION OF OHIO.

IMPULSE-DRIVE MECHANISM FOR MAGNETOS.

Application filed January 2, 1923. Serial No. 610,224.

To all whom it may concern:

Be it known that I, CARL E. PEARSON, a citizen of the United States, residing at Cleveland, in the county of Cuyahoga and State of Ohio, have invented certain new and useful Improvements in and Relating to Impulse-Drive Mechanisms for Magneto, of which the following is a specification, reference being made therein to the accompanying drawings.

This invention relates to mechanisms such as are sometimes used for driving magneto type ignition generators of internal combustion engines, the mechanism being adapted to give the rotor of the magneto a quick rotary movement in order to secure adequate ignition currents even when the engine is being turned over slowly at starting.

One of the objects of the invention is to provide an impulse drive mechanism simple and rugged in construction, easily assembled and disassembled and susceptible of being produced at moderate cost.

Another object of the invention is to increase the life of the drive and buffer spring structures of the impulse drive mechanism, and render said mechanism more reliable in operation.

Another object of the invention is to provide an impulse drive mechanism of the automatic type with improved manually controlled means for rendering the impulsing feature of the mechanism inoperative when desired.

Various other objects more or less incidental or ancillary to the foregoing will appear in the following description of preferred embodiment of my improvement, as shown in the accompanying drawings.

In the drawings, Fig. 1 is a side elevation of an impulse drive mechanism embodying my improvement.

Fig. 2 is a front elevation of the same.

Fig. 3 is a front elevation of the mechanism with some of the parts broken away and some shown in section.

Fig. 4 is a vertical section on the line 4—4, Fig. 7.

Fig. 5 is a fragmentary front elevation of the movable stop device and its securing means.

Fig. 6 is a fragmentary view showing the said movable stop device in section.

Fig. 7 is a section on the line 7—7, Fig. 2.

Fig. 8 is a section on the line 8—8, Fig. 2.

Figs. 9, 10 and 11 are sections on the line 9—9, Fig. 7, showing the parts of the mechanism in the different relative positions which they assume in successive stages of the operation of the mechanism.

Fig. 12 is a section corresponding to Fig. 9 but illustrating a modified form of construction.

Fig. 13 is also a section corresponding to Fig. 9 but illustrating still another form of construction.

Fig. 14 is a side elevation of one of the springs fitted with its strip of felt.

Figs. 15 and 16 are a plan and end view, respectively, of the spring and felt.

Fig. 17 is a fragmentary longitudinal section through the spring and felt.

Referring in detail to the construction illustrated in Figs. 1 to 11, 1 indicates the main frame or casing of the magneto ignition generator which may be of any preferred or known form of construction for magnetos. 2 is the rotor shaft of the generator which is formed with a tapered end in the usual manner to receive the driving connection. 3 is the driven member of the impulse drive mechanism mounted on the tapered end of the shaft 2 and secured against turning in relation to the shaft by the usual key 4. The said driven member comprises a hub part 3^a and a disc or body part 3^b. On the outer end of the hub 3^a is rotatably mounted the driving member 5 of the impulse drive mechanism, the said driving member being operatively secured in position by a washer 6 and a nut 7, the latter being threaded on the end of shaft 2. Obviously the nut and washer also serve to secure the driven member 3 against axial displacement on the shaft. On its outer face the driving member 5 is formed with the usual driving lugs 5^a, 5^b.

On the inner side of the driving member 5 is formed an annular channel 5^b designed to receive the resilient force-transmitting means interposed between the driving and driven members. This force-transmitting means is in the form of two similar springs 8 and 9 and three balls 10, 11 and 12. The springs and balls are arranged in series relation as shown in Fig. 9 so as to form a resilient or spring structure disposed annularly in the driving member 5. Said driving member has its annular channel 5^b

formed with an inward projection 13 having oppositely facing shoulders 13^a, 13^b, which are normally engaged by the walls 10 and 11, said shoulders thus forming abutments for 5 the opposite ends of the annular spring structure. The driving member also has its annular channel 5^b formed with an inward projection 14 which is normally engaged on one side by the ball 12 and thus serves as an 10 abutment for one end of the spring 9. The driven member 3 has rigidly riveted to it an abutment pin 15 which projects from the outer face of said member and fits between the balls 10 and 11, the relative dimensions 15 of the parts being such that when the parts are in their normal positions as shown in Fig. 9 the balls 10 and 11 are in engagement with their abutments 13^a and 13^b and also substantially in engagement with the abut- 20 ment pin 15. At the same time the ball 12 is normally in engagement with the abut- 25 ment 14, the parts being normally held in these relative positions by initial tension of the springs 8 and 9. That is to say said 30 springs are compressed somewhat when they are assembled. The channel 5^b has its ra- 35 dially outward wall undercut as shown in Fig. 7 so as to retain the springs 8 and 9 and the balls 10, 11 and 12. The springs are 40 small enough in diameter to readily enter the channel, being retained after entering by their tendency to spring or bow outward. The balls, however, are of a larger diameter and nearly fill the channel. To permit their 45 entrance into the channel the outer wall thereof is formed with entrance grooves 5^c and 5^d. The outer face of the driven mem- 50 ber 3, where it closes the channel 5^b of the driving member, is formed with a shallow channel 3^e to accommodate the springs 8 and 9 and the balls 10, 11 and 12.

On reference to Fig. 9 it will be seen that the balls 10, 11 and 12, being seated in the end coils of the springs 8 and 9, serve to center the ends of the springs in the channel 5^b and to hold several coils of each spring adja- 45 cent to its ends out of engagement with the walls of the channel 5^b. The significance of this will be referred to below.

50 For purposes which will be more fully explained later I prefer to provide each of the springs 8 and 9 with fibrous spacing means between the coils. In the construction shown I accomplish this by threading strips 55 of felt 16 and 17 back and forth between the coils of the springs 8 and 9, as more particularly illustrated in Figs. 14, 15, 16 and 17.

On the back side of the driven member 3 are 60 mounted a pair of diametrically opposite centrifugally controlled dogs 18, 18. In the construction illustrated these dogs are in the form of pawls mounted on pivots 19, 19. In the same plane with these pawls, 65 the driving member 5 is provided with rear-

ward cam flanges or extensions 20, 20. When the driving and driven members are turned slowly in the direction indicated by the arrow in Fig. 4, the longer, heavier ends 18^a of the pawls 18 successively move inward 70 into engagement with the hub 3^a and thus project the shorter ends 18^b of the pawls outward beyond the periphery of the driving member so that said ends 18^b are caused to engage a suitable stop which will pres- 75 ently be described.

The driving and driven members of the mechanism are partially surrounded by a casing 21 carried by the main frame or cas- 80 ing 1 of the magneto. The casing 21 can be joined to the frame 1 in any desired or suit- able manner but in the preferred construc- 85 tion illustrated it is detachably secured to the magneto frame 1 by a plurality of screws 22. A close running joint is provided be- 90 tween the casing 21 and the cylindrical outer surface of the driving member 5 by a pair of plates 23, 24 and a packing ring 25 of felt, or the like, which is clamped between said plates and projects from the inner edges 95 thereof into engagement with the outer sur- 100 face of the driving member 5. The plates 23 and 24 are detachably secured to the cas- 105 ing 21 by screws 26, 26.

The above mentioned stop which cooper- 110 ates with the dogs 18, is carried by the cas- 115 ing 21 and in the improved construction illustrated is in the form of a square pin or bolt 27 which is slidably mounted in a chan- 120 nel formed in the casing 21 with one of its corners projecting from the inner wall of the casing in position to be engaged by the dogs 18, as indicated in Fig. 3. The stop bolt 27, however, is cut away at its inner and outer ends, as indicated in Figs. 4 and 8, thus 125 leaving only its central portion 27^a effective as a stop for the dogs 18. When the bolt 27 is in the position indicated in Figs. 3 and 8, the part 27^a is in position to be engaged by the dogs 18, but by sliding the bolt out- 130 ward as indicated in Figs. 4 and 6 it is brought to an inoperative position such that it is not engaged by the dogs 18. To secure the stop normally in operative position the casing 21 is provided with a pivoted catch 135 28 mounted on a screw 29 and adapted to swing over the outer end of the stop 27 and hold it in operative position. To effectively 140 secure the catch 28 in engagement with the stop 27, the latter has its outer end fitted with a screw 30 and the catch is formed with a notch 28^a which is adapted to embrace the shank of the screw. Thus when the latch 28 is moved into operative position, as shown in Fig. 2, and the screw 30 is tightened on it, 145 the stop bolt and latch are effectively secured together so as to hold the stop in operative position. At the same time by simply loosening the screw the catch can be swung on its pivot to disengage the stop, and the latter 150

can be moved endwise by grasping the head of the screw 30.

In the operation of the form of apparatus above described, when starting the engine in connection with which the magneto is used, the driving member 5 is turned, in the direction indicated by the arrows in the various figures of the drawings, at the relatively low speed corresponding to the speed of the engine. Referring to Fig. 9, as the member 5 turns in the direction of the arrow driving force is transmitted from it through ball 11, spring 9, ball 12, spring 8, ball 10 and abutment pin 15, to the driven member 3 and in view of the initial tension of the springs 8 and 9, which is sufficient to overcome the magneto pull of the generator, the driven member is moved in unison with the driving member until one of the dogs 18 engages the stop 27, as indicated in Fig. 3. Thereupon the rotary movement of the driven member is stopped while the movement of the driving member is continued. In Figs. 3 and 9, the parts are shown in the positions they occupy at the moment the dog 18 comes into engagement with the stop 27. As the turning movement of the driving member thereafter continues while the driven member remains stationary, the spring structure, comprising the springs 8 and 9, is compressed until the parts reach the relative positions illustrated in Fig. 10 whereupon the cam 20, having moved from its full line position, as shown in Fig. 3, to its dotted line position, effects the disengagement of the dog 18 from the stop 27 and permits the driven member 3 to be snapped forward by the springs 8 and 9, thus causing the generation of an intense ignition current. At the end of the quick movement or impulse of the driven member and the magneto rotor the abutment pin 15, carried by the inertia of the driven member and the rotor, forcibly engages the ball 11 and causes the latter to compress the spring 9 between itself and the ball 12 which engages the abutment 14. The shock is thus absorbed by the spring 9 alone. Fig. 11 illustrates the position of the parts while the spring 9 is absorbing the shock incident to the impulse of the rotor.

With the impulse mechanism fitted with two dogs 18, it will be seen that the rotor of the magneto is given two rapid impulses with each rotation. However, just as soon as the engine speed exceeds a certain predetermined value the unbalanced centrifugal action on the longer ends 18^a of the dogs 18 serves automatically to retract the ends 18^b so that they do not engage the stop 27. Under these conditions the driven member of the impulse mechanism turns in unison with the driving member, the initial tension of the springs 8 and 9 being adequate to transmit the necessary driving force so that

the relative positions of the parts indicated in Fig. 9 are maintained.

In the operation and use of my improved impulse mechanism two desirable functions are performed by the fibrous spacers 16 and 17 with which the springs 8 and 9 are provided. In impulse drive mechanism as previously constructed there has been considerable difficulty due to the breakage of the springs. I have discovered that this breakage of springs is in a large measure at least due to an unequal or nonuniform distribution of the load throughout the spring or springs and that this lack of uniform distribution of the load results, in the case of annularly disposed coiled springs, from the relatively large friction between the coils of the spring and the channel or casing in which it is mounted. In the present invention I have overcome this difficulty in part by the use of the balls 10, 11 and 12 which, as above explained, hold the end coils of the springs out of engagement with the channel walls, the friction between the springs and the said walls being thus very materially reduced. However, even with the three points of support which the three balls provide for the annular spring structure at its two ends and at its middle point, there still remains a substantial frictional engagement between the middle parts of the springs 8 and 9 and the channel wall. I, therefore, supplement the centering action of the balls on the springs by the use of the fibrous spacers 16 which, while they are compressible, serve nevertheless to prevent undue collapse of any two adjacent coils due to frictional engagement of any of the coils with the channel walls. Thus a substantially uniform distribution of the load is secured throughout the spring structure and abnormal deflections with resultant straining and crystallizing of the spring material is avoided. Indeed, I have by means of my improved construction so greatly increased the life of the spring structure that a set of springs initially free from defects will outlast other parts of the mechanism.

It will be understood that the impulse drive mechanism above described is entirely automatic in its operation. That is to say, when the parts are turned slowly, the drive member is intermittently stopped and then released and snapped forward with a quick movement but, as soon as the speed increases to a certain value the stop action ceases and the driving and driven members move in unison. Then if the speed again falls, as with the stopping of the engine, the stop dogs 18 return automatically to their operative positions in relation to the stop 27. Automatic impulse mechanisms of this character as heretofore provided are somewhat troublesome in connection with the timing of engines inasmuch

as such timing involves the slow turning over of the engine by hand and this is interfered with by the engagement of the stop devices of the impulse mechanism. To overcome this objection I have made the above described provision for manually moving the stop 27 to an inoperative position so that the engine can be turned over slowly without interference of the impulse mechanism.

Some of the advantages of the above described form of apparatus are secured by the modified construction illustrated in Fig. 12. This latter construction has a driving member 5' which is formed without any abutment for the ball 12. In substantially every other respect the construction is similar to that above described and consequently it need not be further described, it being understood that the same reference numerals used in the foregoing description are applied to the like parts in Fig. 12, except in the case of the driving member 5'.

In the second modified form of construction illustrated in Fig. 13, the same driving member 5' is employed that is used in the modification of Fig. 12 but the ball 12 is omitted and a continuous single coiled spring 31 is substituted for the two springs 8 and 9 of the other forms of construction. In all other respects the modification shown in Fig. 13 is similar to that first described and with the exception of the driving member 5' and the spring 31, the same reference numerals applied to the first form of construction illustrated are applied to like parts in Fig. 13.

It will be seen that the construction shown in Fig. 12 has the advantage of the three-point ball support for the annular spring structure with consequent reduction in friction between the said structure and the channel walls, just as in the case of the first described construction. In this respect the construction illustrated in Fig. 13 is less desirable than either of the other two forms of construction since the ball supports are provided only at the two extreme ends of the annular spring structure and the frictional resistance between the springs and the channel walls is of necessity greater. However, even without the third supporting ball for the middle of the spring structure the combined effect of the ball support at the two ends and the fibrous spacer used in connection with the spring 31 enables me to secure better results even with the form of construction shown in Fig. 13 than have been secured with any prior construction known to me.

In both of the modifications shown in Figs. 12 and 13 the entire annular spring structure is subjected to the inertia shock of the mechanism as well as to the driving stress. In this respect these two modifica-

tions are less to be desired than the first form of construction in which the entire spring structure, including both the springs 8 and 9 are subjected to the load when the driving and driven members have their major relative movement incident to the stopping of the driven member, while only the one spring 9 performs the function of a buffer to receive the shock of impact when the driven member is suddenly released.

While it is possible to use too short a spring for this buffer function, and serious breakage, in some prior mechanisms, has resulted from the use of buffer springs that were too short, it is also possible to have buffer springs too long to secure the best results.

Bearing in mind that the normal load transmitted through the impulse mechanism is suddenly increased and decreased twice during each revolution due to magnetic interaction of the rotor and stator of the magneto, it will be seen that if a relatively long and flexible buffer spring with a correspondingly long period is employed, the vibratory motion incident to the alternate forward snapping and buffing of the rotor will approach the relatively low speed of rotation more nearly than would be the case with a shorter spring having a shorter period and said vibratory motion will therefore have a greater tendency to combine additively with the magnetic interaction between the rotor and stator so as to result in a rotary movement of the rotor sufficiently irregular to materially interfere with the timing of the engine.

In a word, the best results are secured where the buffer action is performed by a spring as short as may be used without danger of breakage. In the first form of construction described, I secure an operation that is very satisfactory in this respect and at the same time obtain the advantage of using only one form or size of spring, the two springs 8 and 9 being alike and interchangeable.

My improved mechanism lends itself readily to manufacture. Obviously, the number of different parts is relatively small and these are readily produced and in the production of the driving member the channel 5^b is machined out and the abutment projections 13 and 14 are formed simply by withdrawing the milling tool which effects the undercut of the outer wall of the channel. It will be understood that the various parts of the mechanism are suitably hardened in order to insure adequate wearing qualities.

The mechanism is very easily assembled. The balls and springs are readily inserted in the channel in the driving member and the parts thus assembled are readily applied to the driven member by forcing the abutment pin between the balls 10 and 11. Because of their universal symmetry the balls

cannot become displaced in relation to the springs and as the balls are free to turn they are constantly presenting different surfaces for engagement with the various 5 abutments thus obviating objectionable wear of the parts. The felt strips 16 are readily applied to the springs and when once in position never become displaced because the coils of the springs become somewhat im- 10 bedded in the felt. It is to be observed further in connection with the felt spacers that in addition to their spacing function they serve to hold lubricant and in the rare cases of defective springs resulting in break- 15 age they are adapted also to prevent dis- placement and entanglement of the broken spring sections to such an extent as would render the mechanism inoperative.

It will be understood that my invention 20 is not limited to the specific forms of construction which have been shown and described for purposes of explanation but that the scope of the invention is indicated by the appended claims.

25 What I claim is:

1. In an impulse drive mechanism, the combination of a rotary driven member, a rotary driving member adapted to have a limited turning movement in relation to 30 the driven member, means for intermittently stopping and releasing the driven member, a plurality of springs arranged in series relation between the driving and driven members, and abutments cooperatively re- 35 lated to the springs and said driving and driven members in such manner that when relative rotational movement occurs between the driving and driven members in one direction force is transmitted from one of 40 said members to the other through the entire series of springs and when such relative movement occurs in the opposite direction force is transmitted from one member to the other through only part of said 45 series.

2. In an impulse drive mechanism, the combination of a rotary driven member, a rotary driving member adapted to have a limited turning movement in relation to 50 the driven member, means for intermittently stopping and releasing the driven member, two springs arranged in series relation between the driving and driven members, and abutments cooperatively related to the 55 springs and said driving and driven members in such manner that when relative rotational movement occurs between the driving and driven members in one direction force is transmitted from one of said mem- 60 bers to the other through the entire series of springs and when such relative movement occurs in the opposite direction force is transmitted from one member to the other through one only of said springs.

3. In an impulse drive mechanism, the 65 combination of a rotary driven member, a rotary driving member adapted to have a limited turning movement in relation to the driven member, means for intermittently stopping and releasing the driven member, 70 a plurality of springs similar to each other and arranged in series relation between the driving and driven members, and abutments cooperatively related to the springs and said driving and driven members in such manner that when relative rotational movement occurs between the driving and driven members in one direction force is transmitted from one of said members to the other through the entire series of springs and when such relative movement occurs in the opposite direction force is transmitted from one of said members to the other through only part of said series.

4. In an impulse drive mechanism, the 85 combination of a rotary driven member, a rotary driving member adapted to have a limited turning movement in relation to the driven member, means for intermittently stopping and releasing the driven member, 90 a plurality of coiled compression springs disposed in annular series between the driving and driven members, and abutments cooperatively related to the springs and said driving and driven members in such manner that when relative rotational movement occurs between the driving and driven members in one direction force is transmitted from one of said members to the other through the entire series of springs and when such relative movement occurs in the opposite direction force is transmitted from one of said members to the other through only part of said series.

5. In an impulse drive mechanism, the 105 combination of a rotary driven member, a rotary driving member adapted to have a limited turning movement in relation to the driven member, and resilient force-transmitting means disposed between abutments 110 on the driving and driven members and comprising an annularly extending coiled spring structure and balls seated in the end coils of said structure and engaging said abutments.

6. In an impulse drive mechanism, the combination of a rotary driven member, a rotary driving member adapted to have a limited turning movement in relation to the driven member, one of said members being formed with an annular channel, and resilient force-transmitting means disposed in said channel between abutments on said driving and driven members and comprising a coiled spring structure and balls seated in the end coils of said structure and engaging said abutments, said balls and channel being greater in diameter than the 120 125

spring structure whereby the coils of the latter adjacent the balls are held out of contact with the channel walls.

7. In an impulse drive mechanism, the combination of a rotary driven member, a rotary driving member adapted to have a limited turning movement in relation to the driven member, one of said members being formed with an annular channel, and resilient force-transmitting means disposed in said channel between abutments on said driving and driven members and comprising a plurality of coiled springs in series relation and balls seated in the end coils of said springs, the said balls and channel being greater in diameter than the springs whereby the coils of the latter adjacent the balls are held out of contact with the channel walls.

20 8. In an impulse drive mechanism, the combination of a rotary driven member, a rotary driving member adapted to have a limited turning movement in relation to the driven member, one of said members being formed with an annular channel, and resilient force-transmitting means disposed in said channel and comprising two coiled springs in series relation, a single ball between two adjacent ends of said springs and two balls between the other two ends of said springs, one of said rotary members having an abutment interposed between said two balls and the other rotary member having abutments engaging said two balls and the single ball in such manner that when relative rotational movement occurs between said rotary members in one direction force is transmitted from one member to the other through both of said springs and when such relative movement occurs in the opposite direction force is transmitted from one member to the other through only one of said springs.

9. In an impulse drive mechanism, the combination of a rotary driven member, a rotary driving member adapted to have a limited turning movement in relation to the driven member, one of said members being formed with an annular channel, and resilient force-transmitting means disposed in said channel and comprising two coiled springs similar to each other and disposed in series relation, a single ball between two adjacent ends of said springs and two balls between the other two ends of said springs, one of said rotary members having an abutment interposed between said two balls and the other rotary member having abutments engaging said two balls and the single ball in such manner that when relative rotational movement occurs between said rotary members in one direction force is transmitted from one member to the other through both of said springs and when such relative movement occurs in the opposite direction force

is transmitted from one member to the other through only one of said springs.

10. In an impulse drive mechanism, the combination of a rotary driven member, a rotary driving member adapted to have a limited turning movement in relation to the driven member, one of said members being formed with an annular channel and a shoulder projecting into said channel from one side only thereof, and resilient force-transmitting means disposed in said channel between said shoulder and an abutment on the other rotary member and comprising a coiled spring and a ball seated in an end coil of the spring and engaging said shoulder.

11. In an impulse drive mechanism, the combination of a rotary driven member, a rotary driving member adapted to have a limited turning movement in relation to the driven member, one of said members being formed with an annular channel and a shoulder projecting radially inward from the outer wall only of said channel, and resilient force-transmitting means disposed in said channel between said shoulder and abutment on the other rotary member and comprising a coiled spring and a ball seated in an end coil of the spring and engaging said shoulder.

12. In an impulse drive mechanism, the combination of a rotary driven member, a rotary driving member adapted to have a limited turning movement in relation to the driven member, one of said members being formed with an annular channel and a projection on one wall only of the channel formed with oppositely facing abutment shoulders, resilient force-transmitting means disposed in said channel and comprising a coiled spring structure and balls seated in the end coils of said spring structure and engaging said shoulders on the rotary member, and an abutment in the other rotary member disposed between and adapted to coact with either of the said balls.

13. In an impulse drive mechanism, the combination of a rotary driven member, a rotary driving member adapted to have a limited turning movement in relation to the driven member, one of said members being formed with an annular channel, and resilient force-transmitting means disposed in said channel between abutments on said driving and driven members and comprising a coiled spring having compressible fibrous material disposed between its coils and serving to offer resistance to the collapse of the spring.

14. In an impulse drive mechanism, the combination of a rotary driven member, a rotary driving member adapted to have a limited turning movement in relation to the driven member, one of said members being formed with an annular channel, and resil-

ient force-transmitting means disposed in said channel between abutments on said driving and driven members and comprising a coiled spring having a strip of compressible fibrous material threaded back and forth between the coils of the spring and serving to offer resistance to the collapse of the spring.

15. In an impulse drive mechanism, the combination of a rotary driven member, a rotary driving member adapted to have a limited turning movement in relation to the driven member, automatic means for intermittently stopping and releasing the driven member comprising a centrifugally controlled dog mounted on the driven member and a normally stationary stop arranged to be engaged by said dog, said stop being mounted to slide on a line substantially at 20 right angles to the plane of rotation of the rotary driven member whereby it can be moved out of operative position in relation

to the dog, and manually disengageable means for normally holding the stop in operative position.

16. In impulse drive mechanism for magnetos, the combination with a magneto having its drive shaft projecting from one side of its frame, of a rotary driving member, a rotary driven member on which the driving member is supported and which is itself mounted on said shaft, a casing carried by the magneto frame and partially enclosing the driving and driven members and means for forming a running joint between the casing and the driving member comprising a pair of annular plates secured to the casing and a packing ring clamped between said plates slidably engaging the driving member.

In testimony whereof, I hereunto affix my signature.

CARL E. PEARSON.
